(57) **CLAIM**

The ornamental design for a shaving razor cartridge as shown and described.

DESCRIPTION

FIG. 1 is a front perspective view of a design of a shaving razor cartridge of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view thereof.

The broken lines shown illustrate portions of the cartridge and form no part of the claimed design. The dot-dash lines form a boundary to the claimed design and form no part thereof.

1 Claim, 6 Drawing Sheets(56)
